CLAIM

The ornamental design for a handle for cooking utensil, as shown and described.

DESCRIPTION

FIG. 1 is a perspective view of a handle for cooking utensil showing my new design;

FIG. 2 is a side elevational view thereof, the opposite side view being a mirror image of that shown;

FIG. 3 is a top plan view thereof;

FIG. 4 is a bottom view thereof.

FIG. 5 is a left end view thereof; and,

FIG. 6 is a right end view thereof.

The broken line showings on FIGS. 1-4 are illustrative purposes only and form no part of the claimed design.
